UNITED STATES PATENT OFFICE.

EDWARD B. HESS, OF BROOKLYN, NEW YORK.

WIND-SHIELD FOR AUTOMOBILES.

1,243,937.

Specification of Letters Patent. Patented Oct. 23, 1917.

Application filed October 18, 1916. Serial No. 128,375.

To all whom it may concern:

Be it known that I, EDWARD B. HESS, a citizen of the United States, residing at Brooklyn, in the county of Kings and State of New York, have invented certain new and useful Improvements in Wind-Shields for Automobiles, of which the following is a specification.

This invention relates particularly to wind shields for automobiles of the general kind shown in my U. S. Patent No. 1,178,319, of April 4, 1916, in which a three-part shield is shown comprising a main lower section adapted to be fixed in a vertical plane below the line of vision but to be swung inward for purposes of ventilation; an upper section mounted to swing outward to a position above the direct line of vision or to be held in a vertical plane above the main lower section, and a third or auxiliary section so mounted as to stand at times vertically parallel with and close to the main lower section or to be moved upward into the line of vision below the upper section when the latter is extended to serve as a rain guard. In many automobiles the steering wheel is located quite close to the wind shield and it is not possible to elevate and depress an auxiliary section of the kind shown in my former patent when it is directly pivoted at its upper end to the wind shield frame or standards.

The primary object of my present invention is to provide means whereby the auxiliary section may be conveniently raised and lowered in such manner as to clear the steering wheel and whereby said section may be securely held in its adjusted positions.

In carrying out my invention in the preferred way, I provide standards which support the three shield sections, the upper section being pivoted at its upper end to the upper portions of the standards and the main lower section being pivotally connected at its upper end with the middle portions of the standards. The auxiliary section is provided with lateral projections movable vertically in or on guideways with which the standards are provided, and the arrangement is such that the auxiliary section may be held on the inner side of the shield parallel with and close to the main lower section, or it may be raised and then turned through an arc of about 180° and made to assume a position above the main lower sec-

tion and below the upper section when the latter is extended. The guides in or on the standards may be of various kinds. Preferably, slotted guides are used and these may be either straight or inclined, and the projections on the shield sections are so located as to properly coöperate with the slots in guiding the auxiliary section from one position to another. Devices are provided for holding the several shield sections in their adjusted positions.

My improvements are shown in the accompanying drawings in which—

Figure 1 is a perspective view of a wind shield for automobiles with my improvements applied.

Fig. 2 is a view showing in side elevation a part of the front portion of an automobile and in vertical section my improved wind shield. In this figure of the drawings, the upper section is lowered and the auxiliary section is also lowered and is disposed parallel with and close to the main lower section in a plane below the direct line of vision. Dotted lines indicate how the auxiliary section may be first raised and then turned to clear the steering wheel.

Fig. 3 is a view showing in side elevation a part of the front portion of an automobile and in vertical section my improved wind shield. In this figure of the drawings, the upper section is extended forwardly and the auxiliary section is in its raised position above the main lower section and below the extended upper section. When in this raised position, the lower portion of the auxiliary section overlaps the upper portion of the main lower section.

Fig. 4 is a detail view, in section, showing the manner of connecting the auxiliary section with the standards.

Fig. 5 is a detail view showing particularly a locking device which may be employed for holding the sections in their adjusted positions.

Fig. 6 is a detail view, in section, showing a modified construction in which rollers are carried by the auxiliary section and which operates in guide slots in the standards.

Fig. 7 is a detail view, in perspective, showing how the auxiliary section is provided with an arm carrying a pin which operates in a guide slot in a standard and how said pin is provided with a locking nut.

Figs. 8 to 13 inclusive show a modified construction.

Fig. 8 is a view showing in side elevation a part of the front portion of an automobile and in vertical section my improved wind shield. In this figure of the drawings the 5 upper section is lowered and the auxiliary section is also lowered and is disposed parallel with and close to the main lower section in a plane below the direct line of vision.

Fig. 9 is a view similar to Fig. 8 but shows how the main lower section and the auxiliary section may be swung inward to a slight extent for purposes of ventilation.

Fig. 10 is a detail view showing a device 15 which may be employed for pivotally connecting the wind shield sections with the standards and for holding them in their adjusted positions.

Fig. 11 is a detail view showing devices 20 for supporting the auxiliary shield section in its raised position.

Fig. 12 is a view similar to Figs. 8 and 9 but showing the upper section extended and the auxiliary section partially raised in such 25 manner as to clear the steering wheel. This figure of the drawings also shows by dotted lines the manner in which the auxiliary section is turned about its pivots, while being moved to its elevated position.

Fig. 13 is a view similar to Fig. 12, but shows the auxiliary section in its raised position.

Fig. 14 is a perspective view illustrating the manner in which the auxiliary section is 35 supported in the standards.

Fig. 15 is a view showing a reversal of form.

A part of the hood or casing of an automobile is indicated at A and the wind shield 40 is located in the rear thereof. Standards B rise from the automobile body or casing on opposite sides thereof and are rigidly fixed thereto. The three shield sections C, D and E are supported by the standards, prefer- 45 ably in the manner shown. The upper section C is preferably connected near its upper end with the upper ends of the standards, in the manner indicated at c, by suitable devices which serve as pivots and also 50 serve to lock the shield in its adjusted positions. Devices such as shown in Fig. 10 may be used for this purpose.

The upper shield section is so mounted that it may hang in a vertical plane in the 55 direct line of vision when the auxiliary section is lowered, as indicated in Figs. 2, 8 and 9, and when in this position, it may be held firmly in place by the locking devices c, before described; or the upper section may 60 be extended in the manner indicated in Figs. 1, 12 and 13 and held at any desired inclination.

The main lower section D is pivotally connected at its upper end to the middle por- 65 tions of the standards B by devices d which

may be of the kind illustrated in Fig. 10, and which also serve to lock or hold said lower section in any desired position. The main lower section may be held in a vertical plane below the line of vision, as indicated, or it 70 may be swung inward for purposes of ventilation, as shown in Fig. 9, and so held by the devices d.

The auxiliary section E may be constructed in any suitable way, but preferably it 75 comprises a transparent part e having a frame e¹ at opposite sides and at one end e², while one of its edges e³ is frameless.

I have shown in the drawings different ways of mounting the auxiliary section in 80 the supporting frame or standards in such manner as to enable it to be adjusted to the desired extent without coming in contact with the steering wheel. Figs. 1 to 7 of the drawings show one way of doing this, while 85 the remaining figures of the drawings show another way. These two ways are different in detail, but they are generically the same.

Referring to Figs. 1 to 7 inclusive, it will be observed that the auxiliary shield section is suspended in the standards by pins 1 carried by arms or brackets 2, projecting from the sides of the auxiliary section near its upper end. These pins extend through slots 3, formed in the standards and preferably 90 these pins are threaded and engaged by locking nuts 4. In this instance, the slots 3 are straight, vertically arranged slots. When the auxiliary section E is in its lowermost position, as indicated in Fig. 2, the arms or 95 brackets 2 extend forwardly from the auxiliary section and hold the latter in rear of the main lower section D; and when thus lowered the said section may be locked by the nuts 4 and auxiliary fastenings may be also used for holding the auxiliary section steady. Such devices are indicated at 5, and may be sprung controlled pins 6 having operating heads 7 and adapted to engage recesses in the side frame of the auxiliary section. The spring pins, as shown, are made to operate through lugs 8 projecting rearwardly from the standards. When the upper section is extended and it is desired to raise the auxiliary section to the position 100 shown in Fig. 3, the locking devices are loosened and the auxiliary section is lifted, being guided by the pins 1 in the slots 3 and then it is turned in the manner indicated in Fig. 2 and then further turned through an 105 arc of about 180° until it assumes the position shown in Fig. 3. When in this position, it may be locked by the nuts 4 and also by locking devices 5.

The rods 1 may be provided, if desired, 110 with rollers 10, as indicated in Fig. 6, but the operation is smooth and easy without employing rollers. The rods 115

Referring now to Figs. 8 to 14 of the drawings, it will be observed that the prin- 120 125 130

principle of operation is the same as that heretofore explained.

In this case the auxiliary section is suspended in the standards by lateral projections or pins F which are connected in some suitable way with the shield and extend into and move in slots in the standards. In this modification of the invention, the slots in each standard are in the form of an inverted 10 Y, the lower slots g, g¹ converging from their lower ends and joining the vertical slots g². The slots g are on the inside of the shield, the lower end of each slot being in rear of the plane of the lower section D, 15 while the lower ends of the slots g¹ are in front of the plane of the lower shield section. When the auxiliary section is in its lowermost position, it is held by the pins F which may be provided with locking devices 20 f similar to the devices c shown in Fig. 10, these devices being of well known construction.

The auxiliary section carries devices H for holding it in position when elevated, said 25 devices being adapted to engage brackets b projecting outward from the standards and formed with notches b¹. Each device consists of a rod h mounted to slide in a bracket I attached to the front of the auxiliary section. The rod h is provided with a head h¹ and a spring h² normally holds the rod clear of the bracket and standard, as indicated in full lines in Fig. 11, so that the auxiliary section may be swung past the 30 standard when desired. The construction of the device H is, however, such that the rods h may be extended and made to engage the brackets, as indicated by dotted lines in Fig. 11.

40 The three sections may be held in various positions relatively to each other, as indicated in the several figures of the drawings. When the auxiliary section is in its lowermost position, it is suspended from the standards by the pins F and may be 45 locked by the devices shown, such as f, in Fig. 14. The auxiliary section may be tilted inward with the main lower section in the manner indicated in Fig. 9.

50 When it is desired to raise the auxiliary section into the direct line of vision, the devices f are loosened and the shield is first raised in the manner indicated in Fig. 12, the pins moving upward and outward in the inclined slots g and then passing into the vertical slots g² (Fig. 12). When the pins F have moved sufficiently high in the slots g² for the lower end of the shield to clear the steering wheel, the shield section may be 55 turned in the manner shown to bring its lower edge uppermost and then the shield may be lowered, the pins F passing down into the slots g¹. When this is done, the shield will assume the position shown in Fig. 13.

60 In order to hold the shield in this position,

the rods h are drawn laterally outward as indicated in dotted lines, Fig. 11, and made to engage the brackets b.

While I have shown the pins F as extending through slots g, g¹, g², it is obvious that they may be made to extend into correspondingly shaped grooves in the standards. Furthermore, while the slots are shown in the form of inverted Y's, it is obvious that the shape of the slots may be somewhat 75 changed. If preferred, the slots g¹ may be omitted as after the shield is raised to clear the steering wheel, as indicated in Fig. 12, it may be turned and the pins F may be made to rest upon the bottom of the slots g. 80 Therefore, while I have shown the preferred way of carrying out my invention, it will be understood that it involves some broad features where the details of construction may be varied. It is important, however, 85 that the slots, grooves, or other guides should be such that the shield may be first raised sufficiently to clear the steering wheel, then turned and again lowered to occupy a raised position above the lower shield sec- 90

tion. It will be observed by reference to Fig. 13, that when the auxiliary shield section is in its raised position, its lower portion overlaps the upper portion of the main lower 95 shield section so that rain, snow, wind, etc., are prevented from passing through the shield. There is, therefore, a decided advantage in providing guides of such shape that the auxiliary section may be moved 100 from inside the main lower section where it may be readily reached and adjusted, to the outside where it may overlap the main lower section for the purposes above mentioned.

It will be understood that the adjustments 105 of the several shield sections described in connection with Figs. 1 to 7 of the drawings are substantially the same as those shown and described in connection with the remaining figures of the drawings. 110

Fig. 15 is a view of a reversal of form. It will be observed that the bracket attached to the auxiliary shield section contains a slot or way instead of a pin, and which slot is adapted to engage a pin or roll in the 115 standard.

A wind shield constructed in accordance with my invention is simple, can be cheaply manufactured, and is capable of varied adjustments to suit varying conditions. 120

I claim as my invention:

1. A wind shield comprising: supporting means, an upper shield section in the line of vision pivotally supported at its upper end to move into an upwardly inclined rain shed 125 position, a lower shield section normally in a substantially vertical position below the line of vision and supported pivotally to swing into an inwardly inclined ventilating position, an auxiliary shield section nor- 130

- 5 mally parallel to the normal shield section below the line of vision, and sliding and turning connections between the upper end of the auxiliary shield section and the sup-
10 porting means to move said auxiliary shield section inwardly into a ventilating position with the lower shield section or upwardly by sliding engagement and then permitting it to turn into an inverted upright position above and in front of and slightly overlapping the lower shield section when the upper shield section is in its rain shed position.
15 2. A wind shield comprising: supporting means, an upper shield section pivotally connected at its upper end to said support to move it from a normal substantially vertical position into a forwardly inclined rain shed position, a lower shield section pivotally supported at its upper end to the sup-
20 porting means, an auxiliary shield section normally parallel to the lower shield section, sliding and turning connections between the supporting means and the auxiliary shield section permitting it to move
25 upwardly in sliding engagement and then to be turned into an inverted upright position above the lower section, said sliding and turning connection including angularly related slots on one member and projections on the other member engaging said slots.
30 3. The combination with a supporting frame having converging guide-ways inclined upwardly and inwardly toward the central vertical plane of the standards and extensions passing upward from the converged ends of said inclined guides and a wind shield section having lateral projections moving in said guides.
35 4. A wind shield comprising a main lower section, a supporting frame upon which it is mounted and which is provided with converging guides extending upwardly from below the plane of the top of the main lower section and from opposite sides thereof to-
40 ward the top of the frame and an auxiliary shield section having projections entering said guides, the arrangement being such that the auxiliary section may be raised on the inside of the shield to clear the steering wheel, turned to a vertical position above the main lower section and lowered suffi-
45 ciently to overlap the upper portion of the main lower section and to thus exclude wind, rain, etc.
50 5. A wind shield comprising: supporting means, a lower shield section occupying an upright position below the line of vision, an upper shield section normally in an up-
55 right position in the line of vision abutting the upper end of the lower section and pivot-
60

ally supported at its upper end to move it into an outwardly inclined rain shed position, an auxiliary section normally parallel to the lower shield section below the line of vision, and sliding and turning connections between the upper end of the auxiliary shield section and the supporting means to move said auxiliary section upwardly by sliding engagement and then admitting of its being turned into an inverted upright position above and in front of and slightly overlapping the lower shield section when the upper shield section is in its rain shed position.
65 6. A wind shield comprising: supporting means, a lower shield section, unframed at its upper edge, occupying an upright position below the line of vision, an upper shield section, unframed at its lower edge, normally in an upright position in the line of vision and pivotally supported at its upper end to move it into an outwardly inclined rain shed position, an auxiliary shield section normally parallel to the lower shield section below the line of vision and unframed at its upper edge, and sliding and turning connections between the upper end of the auxiliary shield section and the supporting means to move said auxiliary section upwardly by a sliding engagement and then admitting of its being turned into an inverted upright position above the lower shield section when the upper shield section is in its rain shed position thereby affording three unframed edges adjacent each other when the auxiliary section is in its inverted position.
70 80 85 90 95 100 105 110 115

7. A wind shield comprising: supporting means, a lower shield section, unframed at its upper edge, occupying an upright position below the line of vision, an upper shield section unframed at its lower edge, normally in an upright position in the line of vision and pivotally supported at its upper end to move it into an outwardly inclined rain shed position, an auxiliary shield section normally parallel to the lower shield section below the line of vision and unframed at its upper edge, and means for moving the auxiliary section into an inverted upright position above the lower shield section when the upper shield section is in its rain shed position thereby affording three unframed edges adjacent each other whether the auxiliary section is in its inverted upright or in its lower normal position.

In testimony whereof, I have hereunto subscribed my name.

EDWARD B. HESS.
